(57) **CLAIM**

The ornamental design for a paint can lid, as shown and described.

DESCRIPTION

FIG. 1 is perspective view showing a new design for a paint can lid;

FIG. 2 is a side view thereof;

FIG. 3 is a front view thereof;

FIG. 4 is a rear view thereof;

FIG. 5 is a top view thereof; and,

FIG. 6 is a bottom view thereof.

The broken line showing of a paint can is for illustrative purposes only and forms no part of the claimed design.
